UNITED STATES PATENT OFFICE.

GEORGE A. BURNHAM, OF SAUGUS, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

ELECTRICAL APPARATUS.

Application filed April 29, 1924. Serial No. 709,922.

This invention relates to oil immersed electrical apparatus, as electric switches, and switching stations and systems.

When an oil immersed switch is opened under heavy load, oil vapors and gases are or may be generated within the switch casing and under certain conditions explode and thereby impose severed stresses upon, if not actually damage to the switch structure.

An object of this invention is the provision of an oil immersed electric switch with an expansion chamber, the internal volume of which is relatively great as compared with the internal volume of the switch casing, whereby to keep down the internal pressures within the switch.

A further object of the invention is the provision of a switch having an open top enclosing casing adapted to contain the arc-quenching fluid in the bottom thereof and switch-members extended through the casing below the open top, the top-opening being at such a distance above the fluid level in the casing as to retain such amounts of fluid that may be moved upwardly above the normal fluid level during circuit-interruption.

A further object is to provide means insuring the natural and substantially continual ventilation of the switch whereby to maintain it free from an explosive mixture.

A further object is to provide in one structure means for carrying out the above enumerated objects of this invention.

A further object of the invention is generally to improve the construction and operation of electric switches.

Fig. 1 is a sectional elevation through a switching station containing the invention.

Fig. 2 is a sectional detail along lines 2-2 of Fig. 1.

Fig. 3 is a plan detail along lines 3-3 of Fig. 1.

Fig. 4 is a sectional elevation through one of the switch units of Fig. 1 and taken along lines 4-4 of Fig. 1.

Fig. 5 is a vertical sectional detail taken along lines 5-5 of Fig. 4.

Fig. 6 is a view of an outdoor-type electric switch embodying the invention associated with a transmission line.

Fig. 7 is an elevation of the switch of Fig. 6.

Fig. 8 is a vertical sectional elevation of the switch of Fig. 6.

Figs. 6, 7 and 8 illustrate certain features of the invention. The switch includes a casing having the switch frame 10 which preferably is more or less circular. Said frame 10 is formed with an upper neck 11 which forms a venting passage for the escape of oil gases and vapors from the switch. Said switch frame 10 is formed, also, with a lower opening 12 preferably disposed below and in vertical line with the neck opening 11. An oil receptacle 13, preferably cylindrical, is received in said lower opening 12. Said oil receptacle may be secured to the switch frame 10 by suitable means as the tie rods 14; and said receptacle may be removed from the casing by removing the nuts 15 from the ends of said tie rods. Stationary switch members 16 are secured to the switch frame 10 on opposite sides of the neck-opening 11 and extend angularly through said switch frame and into the oil in said receptacle. A movable switch member 17 cooperates with said stationary switch members to control the circuit through the switch. The switch frame 10 is or may be formed or provided with supporting brackets 20, which brackets are disposed on opposite sides of the switch frame and extend outwardly beyond the oil receptacle. Said brackets serve to support the switch in elevated position upon a suitable supporting structure 21 and preferably in such an elevated position thereon that the oil receptacle may be lowered to clear the stationary and movable switch members for the removal of the receptacle from the switch. The switch herein shown is of the outdoor type and in Fig. 6 is interposed between and connected to the conductors 23 and 24 of a transmission line although, obviously, the switch may be otherwise arranged.

It is an object of this invention to make the neck-opening 11 of the switch frame as large in cross sectional area as is commercially practicable and, as is here shown most clearly in Fig. 8, the neck opening is approximately equal in cross sectional area to that of the oil receptacle 13. A conduit 26 is secured to the neck of the switch frame and about the neck opening therein and extends vertically upward for a substantial

distance, say upwards of ten feet. Said conduit is preferably of uniform diameter and is open at its upper end. A rain shield 27 may be secured over the open upper end of 5 said conduit and serve to prevent rain and snow from entering the conduit although not to restrict free and unrestricted communication between said conduit and the atmosphere. As thus arranged, it is apparent that 10 said conduit 26 may function as an exceedingly large expansion chamber for the switch as the volume in said conduit is many times larger than the volume of the switch casing comprising the switch frame 10 and that 15 portion of the oil receptacle above the oil level therein. Due to the large internal dimensions of the conduit, internal pressures set up in the switch casing due to generation of oil gases and vapors therein may be kept 20 down to a relatively low value. Since the conduit 26 is of substantially uniform cross-section throughout its length and is freely open at the top, the switch may vent with the greatest rapidity whereby to keep down 25 internal pressures.

The conduit 26 also functions as a chimney to ventilate the switch automatically and continually. Due to the fact that the temperature of the switch, when carrying current, is, ordinarily, elevated above that of the atmosphere, the gaseous contents of the switch become heated and tend to rise thereby setting up a draft along the vertical height of the chimney. station. Said chimneys may extend through the upper floor of the station containing the bus compartments and pass through the roof ⁵ of the station and open into the atmosphere above the roof. The function of said chimneys 55 are identical with the conduits 26 and set forth in connection with the construction illustrated in Figs. 6, 7 and 8. The switch frame may be provided with a draft 10 inlet opening 30^a and a swinging valve 31^a may be arranged to cover said opening to prevent the discharge of gases outwardly through the opening and swing away from the opening to permit the natural ventilation 15 of the switch caused by the draft set up in the chimneys 55. The upper end of said chimneys 55 may be covered with rain shields 27^a, which shields preferably are so disposed as not to offer appreciable resistance to the 20 escape of gases from the chimneys.

If desired, the natural draft provided by the vertical chimneys may be enhanced by a draft increasing means actuated by lateral air currents circulating about the open upper 25 ends of the conduits. Said draft increasing means may include a head 60 illustrated in connection with the right hand switching apparatus shown in Fig. 1. Said head is freely pivoted on and about the upper end 30 of the right hand chimney 55 and is provided with a vane 61 to maintain it in line with the moving air currents. A draft nozzle 62 may be carried by said head and be in free and unimpeded communication with 35 said nozzle. An induction nozzle 63 may be axially disposed in respect to and open into said draft nozzle 62. The passage of air through said induction nozzle 63 into the draft nozzle serves to set up a forced draft in 40 the chimney 55 thereby to enhance the natural draft thereof.

The chimney 55 and also the conduit 26 may be made of any suitable material as entirely of metal or entirely of some insulating 45 material, or, if desired, the lower ends of said conduits may be made of insulating material in an obvious manner, and the upper ends may be made of metal.

With the construction herein shown the 50 circuit interruption takes place, in effect, at the bottom of a relatively tall chimney, which chimney offers free escape for the arc gases formed. Oil displaced during the circuit interruption may be thrown upwardly 55 to a substantial height within the chimney but will again fall downwardly and be returned to the switch while the oil gases and vapors will be separated from the displaced oil and eventually be discharged into the atmosphere through the open upper end of the chimney and out of proximity with live conductors.

The construction may be otherwise modified without departing from the spirit of the 60 invention.

I claim:

1. An electrical apparatus having a casing adapted to contain a vaporizable fluid, and a gas expansion space above the fluid, and a gas-expansion chamber connected with said 70 casing and in free communication with said gas expansion space, said gas-expansion chamber having approximately the cross-sectional area of the casing and a volume at least as great as the volume of said gas expansion space.

2. An electrical apparatus having a casing adapted to contain a vaporizable fluid, and a gas-expansion chamber connected with said 80 casing and in free communication therewith, said gas-expansion chamber having approximately the cross-sectional area of the casing and a volume at least as great as the volume of said casing and having a free vent-opening over approximately its entire cross-sec- 85 tion.

3. An electric switch having an enclosing casing adapted to contain an arc-quenching fluid, and a gas expansion space above the fluid, and a gas-expansion chamber connect- 90 ed with said casing and in free communication with said gas expansion space, said chamber comprising a conduit of substantial length extended approximately vertically above said switch casing and having trans- 95 verse dimensions comparable with the transverse dimensions of the switch casing.

4. An electric switch comprising the combination of an approximately vertical conduit closed at its lower end and freely open 100 at its upper end having a height which greatly exceeds its transverse dimensions, and having a large and approximately uniform cross-section throughout its height, and adapted to contain a body of arc-quenching fluid in its closed end, and stationary and movable switch members contained in the closed lower end of the conduit.

5. An electric switch comprising a large 110 and tall conduit closed at its lower end and having approximately uniform cross-section throughout its height, and adapted to contain a body of arc-quenching fluid at its closed end, and stationary and movable switch members contained in the closed end 115 of the conduit and immersed in the fluid body.

6. An electric switch including a chimney adapted to contain a body of arc-quenching fluid in the bottom thereof, and stationary and movable switch members immersed 120 in the fluid.

7. An electric switch having a casing adapted to contain an arc-quenching fluid, and means including a chimney arranged in 125 communication with the interior of the casing to provide for a natural ventilation of the casing.

8. An electric apparatus having a casing adapted to contain a vaporizable fluid, and 130

means to provide for a natural ventilation of the casing including a chimney with the interior of said casing and extended to a substantial height thereabove, said casing having means for the entrance of air therein above the fluid level.

9. An electric switch having a casing adapted to contain an arc-quenching fluid, and means to provide for a natural ventilation of the casing including a chimney in free communication with the interior of said casing and extended to a substantial height thereabove, said casing having an air-inlet opening above the oil level in the casing, and means governed by pressure conditions within the casing arranged to close said opening.

10. An electric switch having a casing adapted to contain an arc-quenching fluid, and means to provide a natural ventilation for the switch including a chimney connected with the interior of said casing and extended upwardly thereabove and having its upper end freely open to the atmosphere, and draft-increasing means associated with the chimney to enhance the natural draft thereof.

11. An electric switch having a casing adapted to contain an arc-quenching fluid, and means to provide natural ventilation for the switch including a chimney connected with the interior of said casing and extended upwardly thereabove and having its upper end freely open to the atmosphere, and means to enhance the natural ventilation provided by said chimney including a suction apparatus disposed at the upper end of and in operative communication with the interior of said chimney.

12. An electric switch having an enclosing casing and means to ventilate the casing including a relatively large and tall chimney having its lower end arranged in free communication with said casing and its upper end freely open to the atmosphere, and thermal means including current-carrying components of the switch to establish displacement of gas upwardly in said chimney.

13. An electric switch having an enclosing casing and means to ventilate the casing including a relatively large and tall chimney having its lower end in free communication with said casing and its upper end freely open to the atmosphere and electric heating means including current-carrying components of the switch to establish a displacement of gas upwardly within said chimney.

14. An electric switch having an enclosing casing and means to ventilate the casing including a relatively large and tall chimney having its lower end in free com-

munication with said casing and its upper end freely open to the atmosphere and electric heating means including current-conducting components of the switch to establish a displacement of gas upwardly within said chimney.

15. An electric switching station having a chimney extended upwardly and freely open to the atmosphere, and an electric switch having an enclosing casing connected with said chimney.

16. The combination of a fixed chimney, a movable electric apparatus having a casing arranged for communication with said chimney, and means removably to secure said casing in communication with said chimney.

17. The combination of a fixed chimney, an oil receptacle disposed at the lower end of the chimney, means to secure said receptacle removably in position, and switch members extended into said receptacle.

18. An electric switching station including a chimney having an open lower end and having its upper end open into the atmosphere, and an electric switch having a casing arranged in communication with the open lower end of the chimney.

19. An electric switching station having a lower switch-room, an upper bus-room, a chimney extended through both rooms and having a lower opening into the switch-room and having its upper end freely open to the atmosphere, an electric switch contained in the switch room, said switch having a casing secured in communication with the open lower end of said chimney, and circuit leads extended on opposite sides of the chimney between the switch and the bus room.

20. An electric switch having a casing adapted to contain an arc-quenching fluid in the bottom thereof, said casing having a top-opening which is approximately co-extensive with the cross-section of the casing, and switch-members extended through said casing below the open top.

21. An electric switch having an open-top casing adapted to contain an arc-quenching fluid in the bottom thereof, the open top being of such size as to vent the switch rapidly, and the height of the casing above normal fluid level therein being such as to retain fluid thrown upwardly above the normal fluid level during circuit interruption under any load which leaves the switch in condition to be reclosed immediately and carry the normal load on the switch.

In testimony whereof, I have signed my name to this specification.

GEORGE A. BURNHAM.
